CLOCK

Frederick A. Greenawalt, Pittsburgh, Pa., assignor, by mesne assignments, to Pennwood Company, a corporation of Pennsylvania

Application March 10, 1933, Serial No. 660,226

12 Claims. (Cl. 58—125)

This application is a continuation in part, of my co-pending application Serial #599,128 filed March 16, 1932.

5 My invention relates to time indicating devices and particularly to motor driven clocks.

An object of my invention is to provide a relatively simple and compact form of clock which embodies no dial or hands and which will occupy a minimum amount of space.

10 Another object of my invention is to provide a relatively simple and compact form of clock embodying a plurality of drums located in close side-by-side location relatively to each other, together with drum driving means located wholly 15 within the drums themselves.

Another object of my invention is to provide a means for starting the clock and for continuously indicating the operative condition thereof, said starting and indicating means being actuatable and 20 visible from the front of the clock.

Another object of my invention is to provide a drum support that shall be easily and quickly assembled in proper operative position on a base.

25 Another object of my invention is to provide means for driving a subsequent drum from a preceding drum by means that shall ensure a turning movement of a later drum in a relatively short time.

Other objects of my invention will either be 30 set forth hereinafter or will be apparent from a description of one form of device embodying my invention which is shown in the drawings, in which,

35 Figure 1 is a view in front elevation of a clock embodying my invention and shown as located in a casing.

40 Fig. 2 is a view in vertical section through the clock case only, on the line II—II of Fig. 1, the clock mechanism being shown therein in end elevation.

Fig. 3 is a top plan view of the assembled mechanism of my clock, a portion only of the motor being shown,

45 Fig. 4 is a view in front elevation of the mechanism shown in Fig. 3 of the drawings.

Fig. 5 is a fragmentary view of a part of the mechanism showing more particularly the base, a standard thereon, and one of the drums,

50 Fig. 6 is a vertical sectional view taken on the line VI—VI of Fig. 5,

Fig. 7 is an enlarged fragmentary view of the drum shown in Figs. 5 and 6 to show the method of securing the metal strips on a drum,

55 Figs. 8, 9, and 10 are views showing three con-

secutive positions of the means for driving the second drum by a first drum, and,

Figs. 11, 12, and 13 are views showing three consecutive positions of the means for driving the third drum from the second drum.

In practicing my invention I provide a plurality of drums which are located in side-by-side and closely adjacent positions, each drum having a plurality of flat peripheral faces, the numbers of such faces being in accordance with the time to be indicated thereby. The peripheral length of the flat faces on the different drums is the same, so that the drums are of different diameters, each drum being so supported that one flat face of a drum is coplanar with a similar flat face of each of the other drums. The drums are spaced apart a very small distance and are visible through a single sight opening in a suitable casing.

A single base having a plurality of resilient standards thereon supports the respective shafts 20 on which the individual drums may rotate in a step-by-step movement, such movement being initiated by any suitable driving means, preferably a synchronous electric motor having discontinuous engagement with one of the drums. 25 The clock mechanism is provided with means actuatable and visible through the sight opening to start the clock and to indicate continuously the operating condition thereof.

Referring to Figs. 1 and 2 of the drawings, I 30 have there illustrated a suitable casing 21 which may be of any type and which may be made in various shapes and sizes either of metal, wood, or of any other material suitable for such use and which can be made of ornamental design and shape in order to present a pleasing external appearance. The casing is provided with a sight opening 23 in one wall thereof, which opening is made as small as is possible consistent with other requirements, which will be hereinafter referred 35 to more specifically.

Within the casing 21 there is located a clock mechanism which may be designated generally by the numeral 25 and which is mounted on a base 27 which may be made either of metal or of some 45 other suitable material, such as a phenolic condensation product now well known in the art. The base 27 is provided with a flat vertically-extending face 29 at one end thereof, against which a driving electric motor assembly 31 may be secured as by small machine screws 33. Inasmuch as the details of construction of the motor 31 form no part of my invention, I have illustrated it only to such an extent as may be necessary to show its general construction and the manner in 50 55

which it has been modified by me in accordance with my invention.

The base 27 is further provided with a plurality of resilient arms or standards 35, 37, 39, and 41, which are spaced apart suitable distances. The arms 37 and 39 may be combined with a common lower end portion 43, the lower end of which is unitary with or secured to the top of base 27.

The clock mechanism further includes three drums 45, 47, and 49, each of different diameters and each provided with a suitable number of flat peripheral faces, whose peripheral lengths are the same for all of the drums. Drum 45 is provided with ten faces, drum 47 is provided with 15 six faces, while drum 49 is provided with twelve faces. As was hereinbefore noted, the peripheral length of the faces is the same, while their axial width may be different, it being noted that drum 45 indicates minutes, drum 47 indicates tens of 20 minutes, while drum 49 indicates hours. The drums 45, 47, and 49 are provided with hubs 51, 53, and 55 respectively, each of relatively great length, these hubs being adapted to turn on shafts 57, 59, and 61 respectively. Reference to Fig. 6 25 of the drawings will show that shaft 59 is provided with two reduced end portions, one at each end thereof, these being designated by numerals 63 and 65 respectively. The length of that part of shaft 59 which is of full diameter is slightly longer 30 than the axial length of hub 53 located thereon, with the result that hub 53 and the drum 47 of which it is an integral part will turn freely on shaft 59. The excess length of the main part of shaft 59 over hub 53 is on the order of a few 35 thousandths of an inch, so that while the hub 53 may turn freely between arms 37 and 39 but little axial movement of the drum on its shaft is possible. The general construction of the other drum hubs and of their supporting shafts is the 40 same as set forth above for drum 47.

As was hereinbefore set forth, the respective arms 35 to 41 inclusive are so designed and constructed as to be resilient, and these arms are each provided with relatively small openings 67 there- 45 through near their ends for receiving the end portions of reduced diameter of the shafts 57, 59, and 61 respectively. Assembly of the shafts and of the drums mounted thereon in the resil- 50 ient arms may be easily and quickly effected by inserting one end of a shaft in one of the openings 67 and then springing the other cooperating arm through a small distance sufficient to permit entry of the other shaft end of reduced diameter in the opening 67 in that arm. It will probably 55 be found best to locate drum 47 and its shaft 59 in arms 37 and 39, after which the two end drums 45 and 49 and their shafts 57 and 61 can be located in the cooperating pairs of arms as was hereinbefore set forth. The resilient arms will 60 operate to clamp the shafts between them, thereby preventing any turning movement of the shafts in their bearings. As the hubs of the respective drums are almost as long as the supporting shaft on which they respectively rotate, a relatively 65 large bearing surface is provided for the hubs of the drums resulting in very small wear and in long life.

Referring particularly to Fig. 2 of the drawings, I have there illustrated a small cam disc 69 having a single tooth 71 thereon, this cam 69 being mounted on a shaft caused to rotate through one complete turn or revolution in one minute by motor 31. One end of the hub 51 of drum 45 is provided with a plurality of teeth 73 shown more 75 particularly in Fig. 2 of the drawings, and the

relative location of tooth 71 on disc 69 and of the teeth 73 is such that the drum 45 is turned through one tenth of a complete turn once every minute by the action of the continuously operating driving motor means 31.

In order to ensure the proper location of the respective drums during the time when they are stationary, they are severally provided with recesses in one part of their peripheral structure. Thus drum 45 is provided with ten recesses 75, 10 each of substantially V-shape, on the inside of its peripheral portion and on that side of its central plane adjacent to the clock mechanism 31 in the assembled structure, or on the same side as are the teeth 73 on its hub 51. Means cooperating 15 with these recesses to hold the drum 45 in a given position may comprise a spring 77 having one end thereof fixed to the standard 41 or to some other stationary part, while its other end is bent to substantially V-shape so as to enter one of the re- 20 cesses, the construction and location of this spring being such as to effect the interfit of the free or movable end of the spring with a recess of V-shape.

The drum 47 is provided with an annulus 79 at 25 one side or face thereof, which annulus is provided with a number of recesses 81, of V-shape, which are selectively engaged by a spring 83 which is of the same general shape as spring 77. Drum 49 is provided with twelve recesses 85, of 30 V-shape, on the inside of its periphery, which recesses are engaged by a spring 87 which is of the same general shape as springs 77 and 83. It may be noted that these springs serve not only to hold the respective drums in fixed positions, but that they serve also as means for aiding the turning step-by-step movements of the drums. It is ob- 35 vious that some pressure must be brought to bear upon a drum to cause one of the recesses thereof to be disengaged from its positioning spring and further, that the free end of the spring will move 40 into the next recess with a quick motion.

It has already been hereinbefore set forth that the drum 45 indicating minutes, is actuated by means of the cam 69 to move in steps in its turning motion. The inner periphery of drum 45 is provided at that side thereof opposite to that in which the recesses are located with a single lug 89 which lug is adapted to engage selectively and in sequence one of a plurality of six lugs 91 lo- 50 cated on the adjacent side of drum 47. The paths of movement of the single lug 89 on drum 45 and of any one of the plurality of lugs 91 on drum 47 are illustrated in Figs. 8, 9, and 10. It will be noted that the radius of the circular path of lug 89 is much larger than is the radius of the circular paths of lugs 91. It is of course necessary that the drum 47 be moved through the same length of arc as is drum 45, because of the fact 55 that the peripheral length of the flat faces on all 60 the drums is the same.

Fig. 8 shows the relative positions of driving lug 89 on drum 45 and of one of the driven lugs 91 on drum 47 at the instant when lug 89 has just been moved into engagement with lug 91. Fig. 9 shows the relative positions of the two lugs at that instant of time when both drums have been moved through substantially one half of their step-by-step arcuate turning movement, and it will be noted that lug 89 has been sliding against the 70 adjacent face of lug 91 engaged by it, in an out- 75 wardly direction. This of course is because of the fact that the radius of lug 91 is less than the radius of lug 89.

Fig. 10 shows the relative positions of the drums 75

45 and 47 and of the lugs 89 and 91 at the instant of time when both drums have been moved through their step-by-step motion and are again held stationary by the spring means described above. It will be noted that lug 89 has moved in an outwardly direction relatively to lug 91. I wish to point out here that the relative radial dimensions of lugs 89 and 91 and their locations on the respective drums are such as to cause a turning movement of drum 47 through one sixth of its periphery while drum 45 is turned through one tenth of its periphery.

Referring now more particularly to Figs. 11, 12, and 13 of the drawings, I have there illustrated the paths of movement of the means which I have provided for driving drum 49 in a step-by-step turning movement by drum 47. That face of drum 47 adjacent to drum 49 is provided with a laterally extending lug 93, which may be a part of annular member 79, as is shown more particularly in Fig. 5 of the drawings. The general shape of the tip of the lug 93 in vertical section is triangular for a purpose to be hereinafter described. The inner face of the periphery of drum 49 is provided with twelve angularly extending lugs 95, on that side of the central plane of the drum adjacent to drum 47.

Fig. 11 of the drawings shows the relative positions of lug 93 on drum 47 and of one of the lugs 95 on drum 49, these positions being the ones occupied by these two members just prior to a turning movement of the two drums. It may be noted that the lug 93 has a line engagement only with the adjacent face of lug 95. In this case the radius of lug 93 is only one half that of the radius of lug 95, or substantially so, so that lug 93 will move inwardly relatively to lug 95, and this condition is shown more particularly in Fig. 12 of the drawings where it will be noted that one sharp edge of lug 93 is in engagement with the adjacent face of lug 95 at a point closer to the axis of the shaft on which drum 49 is supported than it was in the position shown in Fig. 11.

Fig. 13 shows the relative positions of the lug 93 and the lug 95 which was engaged thereby during the turning movement of the two drums, and it will be noted that the two lugs are now disengaged from each other, lug 93 moving inside of the inner end face of lug 95 because of the much smaller radius of its circular path of movement relatively to that of lug 95. It is thus evident that I have provided means for actuating any subsequent drum from a preceding drum by means which interengage at only one time in the course of a turning movement of the two drums, which means is located entirely within the contour of the drums not only radially, but also axially thereof, the latter condition particularly making it possible to locate the drums in closely-adjacent side-by-side positions relatively to each other.

It is to be noted further that the dimensions, shape, and location of the respective driving and driven lugs on the inside of the plurality of drums must be selected with great care and precision in order that a drum having ten peripheral flat faces, each of a certain length, may actuate a drum having only six peripheral flat faces of the same length, and further that the drum having the six flat peripheral faces shall properly actuate a drum having twelve such faces of the same peripheral length, in such manner that the angular turning movement of each drum shall be inversely in accordance with the number of faces on its peripheral surface. This action follows of

course from the fact that the drums are provided with polygonal flat faces each of the same peripheral length. The drums are therefore of different diameters, and in order that one face of each drum shall be coplanar with a similar face of the other drums at one place only, the supporting shafts must be located at different horizontal distances from the sight opening 23 in one wall of the casing 21.

Each of the drums is provided with a strip of relatively thin material thereon, these strips being shown in side view in Fig. 2 of the drawings where I have indicated them by numerals 97 and 99, strip 97 being located on drum 49 and strip 99 being located on drum 45. These strips are not shown in Figs. 4 and 5 for the sake of clearness. I prefer to use strips of relatively thin material upon which to imprint, etch, or otherwise apply the proper numerals. On the outer surface of the strip associated with drum 45 there will be located the numerals 0 to 9, while the strip on drum 47 will have the numerals 0 to 5, and the strip on drum 49 will have the numerals 1 to 12 thereon. The ends of a strip are located in a slot 101 provided at one corner of the polygonal peripheral surface of a drum. Reference to Fig. 6 of the drawings will show that I provide two enlarged end portions 103 and 105, one at each axial edge of the peripheral portion of a drum and at the axial ends of a slot 101. That part of a strip which fits into one of the enlarged end portions is spread by some suitable means, such as a small punch, whereby the opposed corners of each strip end portion are spaced apart. This interfitting engagement of a strip, and particularly of its end portions, with a drum prevents any axial movement of a strip relatively to the drum on which it is mounted. The use of these strips not only reduces the cost of the drums, but permits also the use of any style of numerals thereon.

In all of the electrically driven clock mechanisms with which I am familiar, it is necessary to adjust the mechanism, and to start the same, where manual starting is required, from the rear of the mechanism which means some turning movement of the clock on its support when it is normally set up in front of a wall or other surface. In order to overcome this I provide a circular member 107 which may be in the shape of a disc having a knurled periphery operatively associated with some part of either the driving mechanism or of the time-indicating mechanism proper. In this case I have shown it as applied to a shaft of the motor assembly and it is only necessary to give member 107 a short quick downward movement by the finger of an operator in order to start the motor, this of course being based on the supposition that the motor is not self starting.

The sight opening 23 is covered by a suitable bezel which includes a hollow frame 109, which may be substantially rectangular in contour, and which is located in front of and over the sight opening 23. A smaller piece of sheet material 111 provided with a smaller sight opening 113 therein is clamped against the front face of casing 21 and in front of sight opening 23 by the same means utilized to hold the bezel 109 in its proper position, which means may be a plurality of screws 115, which are shown in Fig. 1 of the drawings. The central or intermediate portion of member 111 is bowed outwardly, as is shown more particularly in Fig. 2 of the drawings, the radius of curvature being intermediate that of the three drums, the opening 113 therein be-

ing such that only one face of each drum shall be visible in order to very sharply define the face of the respective drums visible to an observer.

- 5 The bezel 109 has a transparent member 117 such as glass located therein, which member may be held by a suitable frame 119 within the bezel 109, provisions (not shown) being made to permit of removing members 117 and 119 whenever 10 required in order to either start the clock or to reset the drums after such restarting. Attention is drawn particularly to Fig. 1 of the drawings where I have indicated that member 107 is visible from the front of the casing through a 15 suitable opening in member 111 at one side of the three drums. The knurled or toothed periphery of member 107 rotates continuously with the motor and indicates continuously whether or not the 20 clock is operating. It is further obvious that the clock mechanism can be set for the proper or correct instantaneous time by opening the window including the glass 117 and its holder 119, as by a tab or lug 121 (see Fig. 1), after which 25 the clock can be started by a quick downward movement of the projecting rim portion of member 107 and the clock can then be set for the correct time indication by individual turning movements of the three drums in either direction, each independently of the other, until the 30 correct indication as to time is attained.

The device embodying my invention thus provides a motor driven clock mechanism which is composed of a minimum number of cooperating parts, so located relatively to each other as to 35 take up a minimum amount of space and in which the means for driving a subsequent drum by a preceding drum shall be simple and be located within the contour of the drums both axially and radially thereof. The drum peripheries 40 are respectively polygonal in shape, each drum having a different number of flat faces thereon, the peripheral length of the flat faces on the different drums being the same. The diameters of the respective drums are therefore different, 45 and particular means, effective for the desired purpose, are provided so that the turning movement of one drum through an arc equal to substantially the length of one of its flat faces shall cause a turning movement of the next drum 50 driven by it, through substantially the same peripheral movement, which however, means a different amount of angular movement.

The shafts of the respective drums are frictionally clamped between the standards in which 55 they are mounted and are thereby precluded from substantial turning movement as the drums rotate thereon. Each drum is therefore provided with a single bearing member of relatively great length, and as the drums are either made of a light metal or of some composition which can be molded, they are of relatively light weight and the wear between the shaft and the hub is very small, thus insuring a long life of the clock.

60 65 The device embodying my invention includes a simple and effective means for starting the clock assembly from the front thereof, and includes also means for effecting the setting of the clock from the front, both operations being effected after the opening of the cover for the front sight opening.

The movement of a succeeding drum from a preceding one is effected in a small period of time, which I have found to be on the order of 70 75 one second, this quick action being the result of

the cooperation of the parts of the mechanism provided for that purpose.

While I have illustrated and described one form of device embodying my invention now preferred by me, I do not desire to be limited thereto, and the scope of the appended claims are to be construed in accordance with the prior art only.

I claim as my invention:

1. A time indicating device including a drum 10 having a flat-sided polygonal periphery, an axially-extending slot in the periphery and a strip 15 having indices thereon encircling the drum and having its end portions extending into the slot to hold the strip tightly on the drum, the end portions of the slot having lateral recesses, the end portions of the strip being interlocked with said recesses.

2. A time indicating device including a plurality of rotatable drums in close side-by-side position, each drum having a different number of flat faces with numerals thereon which cooperate to indicate the time, means for supporting the drums so that one face of one drum shall be coplanar with one face of each of the other drums, 20 all said faces being of equal peripheral length, and means for driving a succeeding drum by a preceding drum in step-by-step movements, said means including lugs on the inner faces of respective adjacent drums whose paths of rotative movement coincide at one time only in the course of one turn of the drums.

3. A time indicating device including a plurality of rotatable drums in close side-by-side 35 positions, each drum having a different number of flat faces with numerals thereon which cooperate to indicate the time all said faces being of equal peripheral length, means for supporting the drums so that one face of one drum shall be coplanar with one face of each of the other drums 40 and means for driving a succeeding drum by a preceding drum in step-by-step movements, said means comprising a lug on one drum extending laterally to a position within an adjacent drum, said latter drum having a series of spaced lugs 45 extending at an angle to the inner face thereof.

4. A device as set forth in claim 3 in which the cooperating lugs slide one on the other in one radial direction only while in driving engagement.

5. A time indicating device including a base, three spaced standards thereon, the two end standards each having one bearing, the intermediate standard being bifurcated at its outer end and providing bearings in each bifurcation, 55 three shafts supported in said bearings and drums rotatably mounted on the respective shafts in close side-by-side positions, each bifurcation of the intermediate standard extending axially within an end drum.

6. A time indicating device including a plurality of rotatable polygonal drums each having a different number of faces, the peripheral length of the faces on the different drums being the same 65 and means for supporting said drums in close side-by-side positions with one face on a drum coplanar with a face on each of the other drums, said means including two spaced end standards outside of the end drums and a bifurcated intermediate standard, the respective bifurcations being located axially within the outlines of an end drum.

7. A device as set forth in claim 2 in which one of said lugs extends laterally from one drum to a position within the adjacent drum and the 75

other of said lugs extends angularly inwardly relatively to the surface of the drum.

8. A device as set forth in claim 2 wherein one drum is provided with a series of driven lugs and the adjacent drum is provided with a single lug, the series of lugs and the single lug being overlapped at a point displaced laterally from the plane separating the adjacent drums.

9. A time indicating device including a plurality of drums of different diameters all located in close side-by-side relation and being positioned relatively to permit corresponding points of the several drum faces to align along a horizontal line, actuating means for moving certain of said drums by a first drum, said means being located entirely within the drums, said means comprising a single lug extending laterally from certain of said drums and to a point within an adjacent drum, a series of lugs extending radially inwardly from the inner face of the adjacent drum, said single lug being positioned to contact and move each lug of the series in succession whereby to rotate one drum intermittently by its adjacent drum.

10. A time indicating device comprising a casing, a single sight opening therein, a plurality of closely adjacent drums rotatably mounted in the casing and having different numbers of flat peripheral faces of equal peripheral length thereon, means to support the drums so that corresponding flat faces will align with each other and extend coplanar in rear of the sight opening, means

to rotate certain of said drums from an adjacent drum, said means comprising a single lug extending laterally from one drum and to a point within an adjacent drum, a series of lugs extending radially inwardly from the inner face of the adjacent drum in positions to be contacted in sequence by said single lug during each revolution of the latter by its related drum.

11. A time indicating device including a plurality of adjacent drums of different diameters and having different numbers of flat peripheral faces of equal peripheral length, means to drive one of said drums from an adjacent driving drum, said means comprising a series of lugs extending radially inwardly from an inner face of the driven drum, the driving drum being provided with a correspondingly arranged driving lug and positioned to engage said series of lugs in sequence, the relative lengths of said driving lug and the other lugs being so fixed that movement of each lug of the series by contact with the driving lug will rotate the driven drum sufficiently to cause a peripheral face thereon to align with a peripheral face of the driving drum.

12. In a device as set forth in claim 11, wherein the faces of adjacent drums are positioned closely adjacent each other, the lug or lugs on one drum extending laterally therefrom to a point within the other drum whereby to permit the close positioning of said drums.

5
